(57) **CLAIM**

The ornamental design for a fencing wire tensioning bracket, as shown.

DESCRIPTION

FIG. 1 is a front, upper isometric view of a fencing wire tensioning bracket.

FIG. 2 is a front view of the fencing wire tensioning bracket of FIG. 1. The rear view is identical to the front view.

FIG. 3 is a right-side view of the fencing wire tensioning bracket of FIG. 1. The left-side view is identical to the right-side view.

FIG. 4 is a top view of the fencing wire tensioning bracket of FIG. 1.

FIG. 5 is a bottom view of the fencing wire tensioning bracket of FIG. 1.

FIG. 6 is a rear, upper isometric view of the fencing wire tensioning bracket of FIG. 1.

FIG. 7 is a front, lower isometric view of the fencing wire tensioning bracket of FIG. 1; and,

FIG. 8 is a rear, lower isometric view of the fencing wire tensioning bracket of FIG. 1.
